UNITED STATES PATENT OFFICE.

WALTER J. DUDLEY, OF BOSTON, MASSACHUSETTS.

TELEPHONIC APPARATUS.

SPECIFICATION forming part of Letters Patent No. 268,359, dated November 28, 1882.

Application filed June 7, 1880. (No model.)

To all whom it may concern:

Be it known that I, WALTER J. DUDLEY, of the city of Boston, county of Suffolk, and State of Massachusetts, have invented an Improvement in Telephone-Signal Apparatus, of which the following description, in connection with the accompanying drawings, is a specification.

My invention is embodied in a telephone-signal apparatus in which any desired one of a series of stations upon the same circuit may be signaled without affecting the signals at the other stations, and has for its object to provide, in connection with the signal-operating apparatus, a switch for the telephone controlled by mechanism actuated in common with that controlling the operation of the signal, and also controlled by the lever upon which the telephone is supported when not in use in such manner that when the telephone is removed from its hook before the signal apparatus is set in operation it will be introduced in the circuit and retained there during the subsequent operation of the signaling apparatus; but if the telephone be hung up when the signaling apparatus is set in operation it can thereafter be placed in circuit only when the signal is also placed in operative position, thus maintaining secrecy from all the stations except the ones from which and to which a signal has been sent.

The signal-operating magnet and the telephone are herein shown as each placed under control of a circuit-closer operated by controlling mechanism arranged to move in unison in the apparatus of the different stations, it being herein shown as operated with a "step-by-step" movement by an actuating-magnet included in the main circuit. In order to prevent interference between the actuating-magnet and the signal-magnet, the said magnets or their armatures are polarized, so that their respective armatures will be effected by currents of opposite polarity.

The telephone-supporting lever, which is moved by the addition or removal of the weight of the telephone, is provided with a finger arranged to operate the circuit-closer for the signal, so as to remove the latter from circuit when the telephone is removed from its hook. The circuit-closer, which controls the telephone-circuit, is itself controlled by the same mech-

anism as the signal-governing circuit-closer, the telephone being placed in circuit thereby at the same time that the signal is placed in circuit, so that at the station where the signal is operated the telephone will also be in circuit as is desired. The telephone is also placed in circuit by the said mechanism when at its starting-point, which is determined by a stopping device employed to place the controlling mechanism of the different stations in unison, as is necessary for proper operation. The telephone-controlling circuit-closer is also connected with the telephone-supporting lever in such a manner that while the telephone remains suspended on the said lever its circuit-closer will be under the control of the mechanism which controls the signal, and the telephone will consequently be removed from the circuit, except while the said mechanism is at its starting-point or at the point at which the signal for the said station is brought into operative condition. If, however, the telephone be removed from its lever, the latter will remove the telephone circuit-closer from the control of the controlling mechanism, or rather place it in such condition that the telephone will be retained in circuit during the entire movement of the controlling mechanism. By these means a subscriber who desires to communicate with another will, by first removing his own telephone, place it in circuit, so that it will not be removed therefrom by the subsequent movement of the signaling-controlling apparatus, which takes place for the purpose of calling another office on the same line, or, if the called office is on another line, will take place for the purpose of insuring secrecy on the line from which the call was received.

I am aware that a signaling apparatus has been previously employed in connection with a secrecy-switch for the telephone controlled by the same mechanism; but in such apparatus, so far as I am aware, the telephone-controlling switch was not also placed under the control of the telephone-supporting lever, which constitutes one of the main features of my invention.

The armature by which the unisoning or stopping of the controlling devices is effected is of opposite polarity to the one by which the controlling mechanism is actuated, and is arranged to close a short circuit for the signal

and telephone, so that in case either of them shall have its circuit broken the main circuit may still be closed through that station, and thus made effective for the other stations 5 thereon.

Figure 1 is a front elevation of a signaling and circuit-controlling apparatus embodying this invention. Fig. 2 is a side elevation thereof, viewed from the left-hand side of Fig. 1, 10 one of the supports for the main rotating arbor being removed; Fig. 3, a detail showing the telephone-controlling switch and its controlling mechanism; and Fig. 4 is a detail showing the same parts as viewed from the 15 under side, it being a section on line x, Fig. 3; and Fig. 5, a detail showing the stopping device and connected parts as viewed from the right-hand side of Fig. 1.

The devices by which the circuits of the 20 signal-magnet and telephone are controlled are mounted on an arbor, a, shown as provided with a ratchet-wheel, b, actuated with a step-by-step movement by a pawl, c, on an armature-lever, c', pivoted at 2, and provided with 25 an armature, c², which is polarized, so as to be attracted by the influence of currents of one polarity, which, for convenience, are assumed to be positive, passing through the actuating-magnet d, which is included in the main circuit. The said armature-lever is provided 30 with a retracting-spring, c³, by which it is withdrawn from the magnet when the latter is demagnetized or magnetized by a current of opposite polarity to that just mentioned—viz., 35 negative.

The signal-operating magnet e (see Fig. 2) is shown in this instance as included in a loop of the main circuit, the said loop containing a circuit-closer, (shown in Fig. 2, as a spring, f,) 40 which under certain circumstances makes a contact with the stop or anvil piece f' to then close the circuit of the signal-magnet, so that the electric current passing over the main line, will be divided, a sufficient portion passing 45 through the said bell-magnet e to operate its armature. The said bell is shown as a vibrator, and the magnet or its armature is polarized, so that the said armature will be attracted 50 only by currents of the opposite polarity to those by which the actuating-armature c² is attracted.

The condition of the circuit-closer f is determined by the signal-controlling device shown as a disk, g, mounted upon the arbor a, the 55 periphery of which acting upon the end of the circuit-closer f, as shown in Fig. 2, keeps it disconnected from the co-operating point f', except when a notch, 3, in the periphery of the said disk in its rotation arrives at and receives the end of the said circuit-closer f, which 60 is then permitted to make contact with the stop f', thus bringing the bell-magnet e in circuit. The notches 3 are set at different points in the different apparatus, so that only 65 one bell circuit closer is operated at a time in a series of instruments actuated simulta-

neously in the same circuit, as is usual in individual signaling apparatus. The said circuit-closer f, with its controlling-disk g and the actuating mechanism for the said disk, constitute the individual signal-controlling mechanism, which, as far as its relations with the other elements of the present apparatus are concerned, might be replaced by other forms of individual signal-controlling mechanism, 70 many of which are well known.

The telephone-supporting lever j is provided with an arm, j', in proper position to engage the circuit-closer f in the movement of the said lever, which takes place when the telephone 80 is removed therefrom, the said arm then disconnecting the parts f f' and breaking the bell-circuit.

The telephone, which is placed in the main circuit, is controlled by a circuit-closer, h, (see 85 Figs. 3 and 4,) which, when pressed against its co-operating point or stop h', closes a short circuit, thus diverting the electric currents from the telephone. The said circuit-closer h is pivoted at 4, so that it can be moved laterally relative to the end of the point h', as well as be bent toward it, or spring away from it by its own elasticity, and it is connected with a finger, i, upon the usual telephone-supporting hook, j, in such manner that when the said 95 telephone is removed from the hook and the lever j is permitted to rise, it will tend to move the circuit-closer from the position shown in full lines to that shown in dotted lines, Fig. 4. When the telephone is upon its hook, the end 100 of the circuit-closer or spring h is held by the finger i upon the surface of the telephone-controlling device, (shown as a disk, k,) mounted upon the arbor a, the main portion of the periphery of the said disk being adapted to press 105 the said spring h into contact with its stop h' to thus short-circuit the telephone. The said disk k is provided with a notch, 5, located in such relation to the notch 3 of the disk g that it receives the end of the spring h at the same 110 time that the notch 3 receives the end of the spring f. When the end of the spring h is received in the notch 5, the said spring is disconnected from the stop h', so that the currents are obliged to pass through the telephone. 115 The disk k is provided with a second notch, 6, which receives the end of the spring h and thus causes the telephone to be in circuit when the arbor a is in its normal position or at its 120 starting-point, which is determined as herein-after described. When in this position, as shown in Figs. 3 and 4, if the telephone be moved from its hook the finger i will move the circuit-closer h into the position shown in dotted lines, Fig. 4, in which its end rests upon a 125 support, (shown as the periphery of a disk, k'), of such diameter that the said circuit-closer will remain disconnected from its contact-point h', during the entire movement of the disk k', and the telephone will thus be kept in circuit. 130 A flange, k², prevents the circuit-closer h from being moved from the disk k to the

disk k' , except when the apparatus is in its normal position, the said flange being provided with an opening, 7, in line with the notch 6, to then permit such movement of the circuit-closer h .

It will be understood that the disk k' serves merely to support the spring h when removed from the telephone-controlling disk k , and it might be a stationary piece of frame-work, instead of rotating with the arbor a , its function being to guide the end of the circuit-closer back through the notch 7 onto the disk k when again brought to its normal position and the telephone hung up.

The different instruments in the same circuit have their arbors a all stopped in unison by an armature-lever, m , pivoted at 8, and provided with an armature, m' , attracted to release the arbor a by currents of opposite polarity to those by which the armature c^2 is actuated, the said stopping device being and operating substantially the same as in Letters Patent No. 234,663, granted to me January 23, 1880. The said armature-lever m , when its armature m' is repelled from the poles of the magnet d , as is the case when a current of proper polarity to actuate the armature c^2 is passing, will rest against a stop, n , (see Fig. 2,) co-operating therewith to close a short circuit direct from the magnet d to the main line, leaving the station, thus short-circuiting the telephone and its circuit-closer h , so that in case either of the latter should be imperfect the main circuit will still remain intact for the operation of the magnet d . As soon as the current is reversed in the magnet d the armature m' will be attracted, and thus break the said short circuit, leaving the telephone under the control of the circuit-closer h , and the said armature will remain held by its own attraction in this position after the negative current has ceased until it is repelled by the positive currents employed to again actuate the armature c^2 . The main circuit, entering the station, is connected with binding-post 20, from which it is continued by wire 21 to the magnet d , the other electrode of which is connected by wire 22 with the stop h' of the telephone-controlling circuit-closer. The said circuit-closer h is itself connected by wire 23 with the circuit-breaking key K , from which the main circuit is continued by wire 24 to binding-post 25, and thence to the next station. Wire 22 and the key K are connected by wires 26 and 27, respectively, with the terminals of the telephone, so that when the direct or short circuit between the said wire 22 and key K is broken at h the said telephone is brought into circuit. Wire 28, branching from wire 21, includes the signal-magnet e , and is connected with the stop f' , the circuit-closer f being connected by wire 29 with wire 23 and the key k , so that when the parts $f f'$ are in contact the currents will divide between the magnets d and e . The wire 22 is connected with the branch wire 30, passing to the metallic

post m^2 , supporting the armature-lever m , which is thus brought into electrical connection with wire 22, and the stop n of the said armature-lever is connected by wire 31 with the wire 24, so that when the armature m' is repelled, as when the armature c^2 is in operation, a short circuit is closed from the magnet d to the line leading to the next station, thus increasing the certainty of the operation of the said magnet.

In operation, when a subscriber desires to communicate with another, he removes his telephone from its hook, thus bringing the circuit-closer h upon the disk k^2 and removing it from control of the disk k , so that the said circuit-closer will remain open and the telephone in circuit regardless of any subsequent movement of the arbor a . The subscriber will then manipulate the key K , or otherwise produce the signal at the central office, and make known through the telephone what he wishes. The central-office operator will then, by sending a positive current interrupted the proper number of times, rotate the arbors a of the instruments in the circuit upon which the subscriber whom it is desired to call is located until the notches 3 and 6 of the disks g and k are brought into position to receive the ends of the corresponding signal and telephone-controlling circuit-closers f and h at the station it is desired to call, and at no other. A reverse current will then be thrown upon the line, attracting the armature m and setting the signal-bell e which is in circuit in operation. The subscriber hearing his bell thus ringing will remove his telephone from its supporting-lever, the arm j of which will then act upon the spring f to disconnect it from the stop f' , and thus break the circuit of the bell and stop its operation. The telephones at the other stations on the circuit will be shunted by the circuit-closer h , and the flange k^2 will prevent the said circuit-closer from being moved upon the disk k' , to thus bring the telephone into circuit, the finger i being made flexible to admit the movement of the lever j when the telephone is removed at the station called.

The arbor a will be provided with a pointer, a' , (see Fig. 1,) to co-operate with a dial, a^2 , as described in my former patent referred to.

The telephone-lever j may, if desired, operate a shunt from the telephone-coils when the latter is supported thereon in the usual manner.

The arbor a and circuit-controlling devices thereon will preferably be so arranged that the first movement thereof from the common starting-point will bring none of the signals or telephones in circuit, so that in case the subscriber that calls the central office is on a different circuit from the subscriber called, the instruments in the circuit of the said calling subscriber will be moved one space, thus effectively cutting out all other telephones in the said circuit, and at the same time indicating to the other subscriber that the line is in use.

As herein shown, the wires 27 and 26, which

are connected with the terminals of the telephone, are also respectively connected with the telephone-supporting lever j and the stud j^2 , upon which the said lever is depressed by the weight of the telephone when supported thereon, thus completing the short circuit between the wires 26 and 27, and cutting out the telephone.

I claim—

1. The combination of the following elements, namely: the signal, the movable controlling device for the said signal, whereby it is rendered inoperative except during a definite portion of the movement of the controlling device, and the movable telephone-support co-operating with the said signal, substantially as and for the purpose set forth.
2. The combination, substantially as hereinbefore set forth, of a circuit-closer, mechanism controlling the condition of the said circuit-closer in connection with others of a series, a telephone-supporting device, and mechanism operated by the said device, whereby the said device when relieved of the weight of the telephone before the mechanism controlling the said circuit-closer is set in motion, removes the said circuit-closer from control of the said mechanism which controls it in connection with others of a series.
3. In a telephone-signal apparatus, the combination of the telephone-supporting hook and its flexible finger, of the circuit-closer connected with the said flexible finger, substantially as and for the purpose described.

4. The combination, substantially as hereinbefore set forth, of a circuit-closer, a telephone-supporting device operatively connected with the said circuit-closer, a movable device for controlling the condition of the said circuit-closer, and mechanism connected therewith, whereby, when the said movable device is in a certain position, the circuit-closer may be removed from its control by the action of the telephone-supporting device; but when the said movable device is in any other position the circuit-closer is retained in its control.

5. In a telephone-signal apparatus, the telephone-supporting lever and telephone-controlling circuit-closer, combined with the controlling disk and support for the latter, the said circuit-closer being operated by the controlling-disk to govern the circuit of the telephone, and being operated by the said supporting-lever to remove it from or restore it to the control of the said disk, substantially as described.

6. The combination, substantially as hereinbefore set forth, of a signaling or communicating instrument, an electro-magnet in circuit therewith, an armature actuated by currents of one polarity only when such instrument is not in use, a shunt or short circuit for said instrument and circuit-closer therein controlled by the said magnet, and another armature oppositely polarized to the first.
